CATHODE RAY TUBE CONTROL CIRCUITS

Rudolf Urtel and Robert Andrieu, Berlin, Germany, assignors to Telefunken Gesellschaft für Drahtlose Telegraphie m. b. H., Berlin, Germany, a corporation of Germany

Application July 15, 1936, Serial No. 90,706
In Germany July 8, 1935

1 Claim. (Cl. 250—27)

The invention relates broadly to control circuits for cathode ray tubes and more specifically to a circuit arrangement whereby the production of the cathode ray beam in the tube may be blocked or diminished when the deflecting means for the tube are being energized in such fashion as to return the beam to some initial or base point from a position to which it has been previously deflected.

10 This is particularly important where the cathode ray tube is employed as a television receiving element and where the beam has swept across one line of the picture and must be returned to the beginning of the line without affecting the 15 picture detail. If the beam is allowed to sweep back across the fluorescing screen with any intensity, the fluorescent screen is brightened for that line and hence picture detail is affected as well as a flicker effect being produced.

20 According to the invention, a portion of the energy used to return the beam to the initial point, or an energy operating synchronously therewith, is joined in series to a rectifier, in this instance, a dry rectifier, which is triggered by a biasing 25 arrangement, as for instance, a steady voltage, so that the rectified energy produces a voltage in excess of the triggering voltage and the excess is used as a blocking voltage in the control circuit for the cathode ray beam.

30 The invention will best be understood by reference to the accompanying drawing in which:

Figure 1 shows a schematic embodiment of our invention.

Figure 2 shows a modified arrangement according to Figure 1, and

Figure 3 shows still another embodiment of our invention.

Referring to Fig. 1, 10 represents a coil connected in the deflection energy circuit of the cathode ray tube, and may be the magnetic deflection coil of the tube itself. Inductively coupled thereto is a coil 11 across which is connected a loading resistor 12. Joined in series with this parallel arrangement is a rectifier 13, a resistance 15 and a biasing voltage 14. The direction of the induced voltage in the coil 11 when the beam is being returned to its initial position is indicated by the positive and negative signs thereon. Joined in series with the resistor 15 is the secondary 45 of a transformer 19 whose primary is energized by the picture signals with which the cathode ray beam is modulated, the control electrode of the tube 16, said control electrode being indicated as 20, a biasing voltage 18 and the cathode 50 of the tube 17.

The circuit arrangement shown in Fig. 1 functions in such a fashion that during the energizing of the deflecting members of the tube 16 in such manner as to return the beam to its initial position, there appears in the coil 11 a voltage, the 5 direction of said voltage being indicated by the positive and negative signs on the diagram. The direction of this voltage is such as to oppose that of the biasing battery 14 and hence, if it is greater than the value of the voltage 14, it will cause a 10 current to flow through the series circuit comprising the coil 11, rectifier 13 and resistor 15. The resistor 15 being connected in series with the cathode 17 of the tube 16, the secondary of transformer 19 and a control electrode 20 of the tube, 15 the control electrode 20 will be biased with respect to the cathode of the tube by an amount equal to the voltage drop across resistor 15, and hence if the value of this voltage be sufficient, the 20 cathode ray beam would be blocked.

When the deflecting members of the tube have returned to a state wherein the cathode ray beam, if produced, would impinge at the initial point, the direction of the deflecting voltage changes so as to sweep the beam back again linearly across 25 the screen. During this time the voltage induced in coil 11 would be in a direction opposite to that indicated by the signs, hence coil 11 would tend to oscillate at its natural frequency due to the collapse of current through the rectifier. The resistor 12 acts as a damping member to suppress 30 the production of a voltage on the positive half of the oscillation which might exceed the value of the biasing battery 14 and hence cause a rectified current whose voltage drop across the resistor 15 would tend to either substantially reduce 35 or entirely block the production of the cathode ray beam.

The arrangement shown in Fig. 2, substitutes an auto-transformer arrangement for the two 40 coils 10 and 11 of Fig. 1. In this case the potentials opposite to that in the arrangement shown in Fig. 1 and therefore the rectifier connections and biasing member are changed accordingly, that is to say reversed. The voltage drop through 45 resistor 15 is opposite to that in Fig. 2 and therefore the control electrode and the cathode are suitably connected thereto or, in other words, the connections to the resistor 15 are, in Fig. 2, reversed in position from those shown in Fig. 1. 50 The operation of the circuit is the same.

Referring to Fig. 3, the resistor 15 has been supplanted in position by the rectifier 13 and it is the potential across the rectifier and not across the resistor which serves the control elements of 55

the tube. In this case, in order to limit the current passing through the rectifier, it is advisable to provide a resistor element 21 connected as shown in the diagram. The direction of the potential source 14 and the rectifier in Fig. 3 correspond to those in Fig. 1. However, it is obvious that the circuit may be modified in the manner suggested in Fig. 2.

What we claim is:

- 10 An apparatus for controlling the production of a cathode ray beam, a cathode ray tube having an electromagnetic beam deflection coil for deflecting the cathode ray beam comprising a deflection

voltage circuit, a deflection coil energized from said circuit, electrical means coupled to the coil connected to the deflection voltage circuit so that the coupled coil forms a transformer secondary and derives energy from the deflecting coil, a first series electrical circuit comprising said coupled electrical means, a rectifier and a resistor, a second series circuit comprising a control electrode of the cathode ray tube, the aforementioned resistor, the cathode of the cathode ray tube and 10 a source of modulating potential.
